FRACTIONATION CONTROL

Donald R. Wienecke, Borger, Tex., assignor to Phillips Petroleum Company, a corporation of Delaware
Filed Mar. 1, 1962, Ser. No. 176,724
3 Claims. (Cl. 202—160)

This invention relates to the computation of internal reflux in fractionation columns. In another aspect it relates to the control of fractionation columns in response to computations of internal reflux.

It is known that even small changes in the temperature of reflux returned to a fractionation column can create disturbances which are so severe that control instruments employed on the column must be detuned to preserve stability. Unless the reflux temperature is controlled rather precisely, the overall control system can operate in an oscillatory manner. This situation has been observed on many fractionation columns equipped with conventional control instruments.

It has recently been discovered that the control of fractionation columns can be improved by computing and regulating the internal reflux in the column. Internal reflux constitutes the external reflux returned to the column plus the vapor which is condensed near the top of the column by sub-cooled external reflux. This internal reflux R_i can be computed from the following equation:

$$R_i = R(1 + K\Delta T)$$

where R is the external reflux returned to the column, ΔT is the difference between the temperatures of the overhead vapor and the external reflux, and K is equal to the specific heat of the liquid on the top tray divided by the heat of vaporization of liquid on the top tray. Apparatus which can be employed to solve this equation and to control fractionation columns in response thereto is described in detail in ISA Journal, June 1959, pages 34 et seq.

In most fractionation systems, the internal reflux computer described in the above-mentioned article provides efficient control of the external reflux flow. However, this system does not always provide the desired accuracy if only a portion of the overhead vapors are condensed. When this occurs, the external reflux returned to the column does not have the same composition as the overhead vapors removed from the column. In accordance with the present invention, a novel system is provided for computing the internal reflux to be supplied to a column when only a portion of the overhead vapors are condensed. This computation is made from measurements of the rate of flow of the overhead vapors, the rate of flow of external reflux, the temperature of the overhead vapors, the temperature of the external reflux returned to the column, and the temperature of the vapors passed upwardly to the top tray in the column. Signals representative of these measurements are combined so as to provide a computed value of the internal reflux within the column. A signal representative of this internal reflux can then be employed to control the operation of the column to maintain desired steady-state conditions. This control can be made automatically or by an operator from the information provided.

Accordingly, it is an object of this invention to provide a system for computing the internal reflux in a fractionation column.

Another object is to provide control systems for fractionation columns, which systems utilize computations of the internal reflux in the columns.

Another object is to provide a method of and apparatus for computing internal reflux in fractionation systems wherein only a portion of the overhead vapors are condensed to supply external reflux.

2

Other objects, advantages and features of the invention should become apparent from the following detailed description, taken in conjunction with the accompanying drawing which is a schematic representation of the fractionation control system of this invention.

Referring now to the drawing in detail, there is shown a conventional fractionation column 10 which is provided with a number of liquid-vapor contacting trays, three of which are shown schematically in the top section of the column. A feed mixture to be separated is introduced into column 10 through a conduit 11 at a predetermined rate which is maintained by a flow controller 12 that adjusts a valve 13. Steam, or other heating medium, is supplied to the lower region of column 10 through a conduit 14 at a predetermined rate which is maintained by a flow controller 15 that adjusts a valve 16. A kettle product stream is withdrawn from the bottom of column 10 through a conduit 18 which has a control valve 19 therein. The rate of kettle product withdrawal is regulated by a liquid level controller 20 which adjusts valve 19 so as to maintain a predetermined liquid level in the bottom of column 10.

Vapors are withdrawn from the top of column 10 through a conduit 22 which communicates with the inlet of a condenser 23. A suitable coolant is circulated through condenser 23 from a conduit 24 which has a control valve 25 therein. The outlet of condenser 23 is connected by a conduit 26 to a reflux accumulator 27. The vapors which are not condensed are withdrawn from accumulator 27 through a conduit 28 as an overhead product stream. A pressure controller 29 adjusts a valve 30 in conduit 28 so that the vapors are withdrawn at such a rate as to maintain a predetermined pressure within accumulator 27. The condensate in accumulator 27 is returned to the top of column 10 through a conduit 31 to provide reflux to the column. A liquid level controller 32 on accumulator 27 regulates valve 25 so as to maintain a predetermined liquid level in the accumulator. This assures that sufficient vapors are condensed to provide the required reflux to the column.

In order to explain the operation of the internal reflux computer and control system of this invention, an equation will be derived which is representative of the internal reflux in the fractionation column.

The first basic relationship employed in this derivation is

$$Q = WH \quad (1)$$

where Q is the total enthalpy of a stream (B.t.u./hour, for example), W is the flow rate of the stream (pounds/hour, for example), and H is enthalpy of the stream (B.t.u./pound, for example). The second basic relationship is

$$H = (T \cdot C) + C' \quad (2)$$

where T is the temperature of a stream ($^{\circ}$ F., for example), C is a constant expressing the relationship between temperature and enthalpy of the stream, and C' is a constant to adjust the enthalpy base to a reference temperature.

The heat balance at the top of the fractionator can be expressed as

$$Q_{ir} = Q_{er} + Q_v - Q_{oh} \quad (3)$$

where Q_{ir} is the enthalpy of the internal reflux flowing downwardly from the top tray of the fractionator, Q_{er} is the enthalpy of the external reflux returned to the fractionator, Q_v is the enthalpy of the vapor rising to the top tray, and Q_{oh} is the enthalpy of the vapors removed from the top of the fractionator. The corresponding material balance can be expressed as

$$W_v = W_{oh} - W_{er} + W_{ir} \quad (4)$$

where the subscripts have the same meanings as noted with regard to the Q terms.

Equation 3 can be modified by substituting Equation 1 to obtain

$$W_{ir}H_{ir} = (W_{er}H_{er}) + (W_vH_v) - (W_{oh}H_{oh}) \quad (5)$$

The value of W_v of Equation 4 can be substituted into Equation 5 to obtain

$$W_{ir}H_{ir} = (W_{er}H_{er}) + [(W_{oh} - W_{er})H_v] - (W_{oh}H_{oh}) \quad (6)$$

Equation 6 can be rearranged to obtain

$$W_{ir} = \left[\frac{W_{er}H_{er}}{H_{ir} - H_v} \right] + \left[\frac{(W_{oh} - W_{er})H_v}{H_{ir} - H_v} \right] - \left[\frac{W_{oh}H_{oh}}{H_{ir}H_v} \right] \quad (7)$$

The quantity W_{ir} is the internal reflux.

The computer of this invention solves Equation 7. A temperature sensing element 40 is disposed in conduit 22 to measure the temperature of the vapors removed from the top of column 10. It is assumed that these vapors are at substantially the same temperature as the internal reflux in the column because the vapors leaving the top tray are essentially at equilibrium with the liquid leaving the top tray. Element 40 is connected to the input of a temperature transducer 41. This transducer can be any commercially available instrument which is provided with both a scale factor and an adjustable zero point. These two factors can be adjusted so that the output signal from transducer 41 is representative of H_{ir} , assuming the composition of the internal reflux does not change materially. The output signal from transducer 41 is applied to the first input of a summing element 42 and to the first input of a subtracting element 43. Summing element 42 is supplied with a reference signal which is representative of the heat of vaporization of the liquid in the upper region of the column. This is added to the input signal H_{ir} such that the output signal from element 42, which is transmitted to the first input of a multiplying and dividing element 44, is representative of the quantity H_{oh} .

A second temperature detecting element 45 is disposed within column 10 to measure the temperature of the liquid descending from the second tray from the top of the column because the temperature is indicative of the average temperature of the vapors to the top tray. This detecting element is connected to the input of a temperature transducer 46 which is calibrated to provide an output signal representative of the quantity H_v . This signal is applied to the second input of subtracting element 43 so that the output signal from element 43 is representative of the quantity $(H_{ir} - H_v)$. This signal is supplied to an input of the element 44. The third input signal to element 44 is representative of the rate of flow of the overhead vapors. Such a signal can be established by a differential pressure transmitter 47 which is connected across an orifice in conduit 22 and transmits a signal to the input of a square root element 48. Element 48 is calibrated such that the output signal W_{oh} is representative of the rate of flow of overhead vapors. The output signal from element 44 is supplied to one of the inputs of a summing element 49.

A second differential pressure transmitter 50 is connected across an orifice in reflux conduit 31. The output signal from transmitter 50 is applied through a square root element 51 to the input of a subtracting element 52 and to the input of a second multiplying and dividing element 53. The second input signal to element 52 is the output of square root element 48. The output of element 52 is applied to the first input of a third multiplying and dividing element 54. Network 54 also receives input signals from transmitter 46 and element 43. The output of element 54 constitutes the second input to summing element 49.

A third temperature sensing element 55 is disposed in conduit 31 near column 10. Element 55 is connected to the input of a temperature transmitter 56 which is calibrated to provide an output signal H_{er} which is applied to the second input of element 53. The output signal

from element 53 constitutes the third input to summing element 49. Element 49 adds the output signal from element 54 to the output signal from element 53 and subtracts the output signal from element 44. The output signal from element 49 is thus representative of the quantity W_{ir} , as noted in Equation 7. This signal is applied to a flow recorder-controller 60 which adjusts a valve 61 in reflux conduit 31. Controller 60 is provided with a set point signal which represents the desired rate of flow of internal reflux in the column. This, of course, can be computed for any given fluid mixture and desired separation thereof. If the computed internal reflux should deviate from this desired value, a signal is applied to controller 60 from network 49 which adjusts the setting of valve 61 to return the computed value of the internal reflux to the desired value. For example, if the computed value should fall below the set point, valve 61 is opened further to increase the rate of flow of external reflux.

As a specific example of the operation of this invention, reference is made to the use of column 10 as a de-ethanizer. Typical rates of flow and compositions are set forth in the following table:

[Basis: 10,000 moles of feed]

Component	Feed	Kettle Product	Overhead Vapor	Overhead Product	External Reflux
Carbon dioxide	33	0	60	33	17
Hydrogen sulfide	336	59	576	277	299
Methane	444	0	532	444	133
C ₂ Hydrocarbons	1,580	80	2,823	1,500	1,328
C ₃ Hydrocarbons	3,646	2,620	3,294	1,026	2,268
Isobutane	480	451	151	29	122
Normal Butane	1,674	1,620	331	54	277
Isopentane	433	437	15	1	14
Normal Pentane	564	564	10	0	10
C ₆ Hydrocarbons	522	522	1	0	1
C ₇ + Hydrocarbons	233	233	0	0	0
	10,000	6,636	7,838	3,364	4,474
Flow (gallons)	111,100	80,300			44,200
Flow (Mcf.)			2,930	1,280	
Temperature (°F.)	170	240	130	95	95

The required enthalpy values for these and other fluid mixtures can readily be determined either from calculations or actual measurements of fluid samples. The compositions at the points of temperature measurement can be determined by withdrawing fluid samples from these points and analyzing the withdrawn samples.

From the foregoing description it should be evident that an improved procedure is provided for computing internal reflux in fractionation columns. This procedure is particularly valuable where only part of the overhead vapors are condensed to provide the external reflux. While the invention has been described in conjunction with a presently preferred embodiment, it should be evident that it is not limited thereto.

What is claimed is:

1. In a fractionation system wherein a fluid mixture to be separated is introduced into a fractionation column; a kettle product stream is removed from the lower region of said column; vapors are withdrawn from the upper region of said column; a portion of said vapors are condensed; and resulting condensate is returned to the upper region of said column as external reflux; a control system comprising means to sense the temperature of the vapors withdrawn from said column and to establish a first signal H_{ir} in response thereto, said signal H_{ir} being representative of the enthalpy of the internal reflux in said column at a region immediately below the point of introduction of external reflux to the column; means responsive to said first signal to establish a second signal H_{ov} representative of the enthalpy of the vapors withdrawn from said column; means to sense the temperature of said external reflux and to establish a third signal H_{er} in response thereto, said signal H_{er} being representative of the enthalpy

of said external reflux; means to sense the temperature in said column a short distance below the point at which said external reflux is returned and to establish a fourth signal H_v in response thereto, said signal H_v being representative of the enthalpy of vapor in said column at the region the temperature is sensed; means to measure the rate of flow of overhead vapors from said column and to establish a fifth signal W_{oh} representative thereof; means to measure the rate of flow of external reflux and to establish a sixth signal W_{er} representative thereof; means responsive to said first, second, third, fourth, fifth and sixth signals to establish a seventh signal W_{ir} which is equal to the quantity

$$\left[\frac{W_{er}H_{er}}{H_{ir}-H_v} \right] + \left[\frac{(W_{oh}-W_{er})H_v}{H_{ir}-H_v} \right] - \left[\frac{W_{oh}H_{oh}}{H_{ir}-H_v} \right]$$

and means responsive to said seventh signal to adjust the rate of flow of said external reflux.

2. The control system of claim 1 wherein said means to establish said seventh signal comprises means to subtract said fourth signal from said first signal to establish an eighth signal $(H_{ir}-H_v)$, means to multiply said second signal by said fifth signal and to divide the product by said eighth signal to establish a ninth signal

$$\frac{W_{oh}H_{oh}}{H_{ir}-H_v}$$

means to multiply said third signal by said sixth signal and to divide the product by said eighth signal to establish a tenth signal

$$\frac{W_{er}H_{er}}{(H_{ir}-H_v)}$$

means to subtract said sixth signal from said fifth signal to establish an eleventh signal $(W_{oh}-W_{er})$, means to multiply said eleventh signal by said fourth signal and to divide the product by said eighth signal to establish a twelfth signal

$$\frac{(W_{oh}-W_{er})H_v}{(H_{ir}-H_v)}$$

and means to add said tenth signal to said twelfth signal and to subtract said ninth signal from the sum to establish said seventh signal.

3. In a fractionation system wherein a fluid mixture to be separated is introduced into a fractionation column; a kettle product stream is removed from the lower region of said column; vapors are withdrawn from the upper region of said column; a portion of said vapors are condensed; and resulting condensate is returned to the upper region of said column as external reflux; apparatus for computing the internal reflux in said column comprising means to sense the temperature of the vapors withdrawn from said column and to establish a first signal H_{ir} in response thereto, said signal H_{ir} being representative of the enthalpy of the internal reflux in said column at a region immediately below the point of introduction of external reflux to the column; means responsive to said first signal to establish a second signal H_{ov} representative of the enthalpy of the vapors withdrawn from said column; means to sense the temperature of said external reflux and to establish a third signal H_{er} in response thereto, said signal H_{er} being representative of the enthalpy of said external reflux; means to sense the temperature in said column a short distance below the point at which said external reflux is returned and to establish a fourth signal H_v in response thereto, said signal H_v being representative of the enthalpy of vapor in said column at the region the temperature is sensed; means to measure the rate of flow of overhead vapors from said column and to establish a fifth signal W_{oh} representative thereof; means to measure the rate of flow of external reflux and to establish a sixth signal W_{er} representative thereof; and means responsive to said first, second, third, fourth, fifth and sixth signals to establish a seventh signal W_{ir} which is equal to the quantity

$$\left[\frac{W_{er}H_{er}}{H_{ir}-H_v} \right] + \left[\frac{(W_{oh}-W_{er})H_v}{H_{ir}-H_v} \right] - \left[\frac{W_{oh}H_{oh}}{H_{ir}-H_v} \right]$$
